SHIRT

Arthur Powell, Montclair, N. J.

Application December 7, 1943, Serial No. 513,277

3 Claims. (Cl. 2—116)

My invention relates to the art of shirt construction and particularly to the collars thereof.

The invention has for an object to provide a shirt with a collar that can be worn as a sport shirt with the shirt open at the throat or worn as a dress shirt with a necktie, the construction being such that the collar, when worn without a necktie, will lie back as smoothly as the collar on an ordinary sport shirt, but when buttoned and worn with a tie will have the necessary reinforcement to look neat in the front, like a dress collar.

Other objects will in part be obvious and in part be pointed out hereinafter.

To the attainment of the aforesaid objects and ends the invention still further resides in those novel details of construction, combination and arrangement of parts all of which will be fully described in the following detailed description and then be particularly pointed out in the appended claims reference being had to the accompanying drawing in which:

Fig. 1 is a fragmentary front elevational view of a shirt in accordance with my invention with the collar in the open or "sport" position.

Fig. 2 is an elevational view of a collar per se.

Fig. 3 is a cross section on the line 3—3 of Fig. 2.

Fig. 4 is a similar cross section with the collar folded over.

Fig. 5 is an elevational view of the collar lining and the attached fold-forming and reinforcing means.

Fig. 6 is a view similar to Fig. 1 but showing the collar buttoned and serving as a dress collar.

In the drawing in which like numerals and letters of reference indicate like parts in all the figures, 1 represents the shirt to which the collar of my invention is attached by sewing as shown in Figure 1.

The collar includes two like fabric facings 2 and 3 and an inner liner 4. The liner 4 is usually made of woven material, preferably such as is usually used in collars for shirts of the kind referred to. The inner liner 4 has substantially the same contour as and is substantially co-extensive with the facings 2, 3.

Secured to the liner 4 in any approved way, as for example by means of an insoluble cement or by stitching is a fold-forming and reinforcing means composed of a central portion 6 and two end portions 5 separated one from another by gaps 8. The reinforcing and fold-forming member extends from one end edge of the collar and liner to the other (see Figs. 2 and 5) and the

fold line 7, 7^a curves or tapers downwardly from the mid-portion 6 toward the ends of the portions 5 which are remote from the central portion or section 6.

The portions or sections 5 do not terminate short of the end edges 10 of the wings 2^a but extend along such edges, from the inner edge 9 of the collar, a substantial distance, a distance approximately equal to the narrowest width of an ordinary necktie.

The gaps 8 between the members 6 and 5 leave un-stiffened areas at which the collar can fold when the shirt is worn as a sport shirt and when it lies flat after laundering.

15 In the drawing S indicates stitching.

I am aware that prior to my invention a combination sport and dress shirt has been suggested, the collar of which is provided with tabs and a special fold-forming guide of one piece which extends around the back and sides of the collar and terminates in pointed ends short of the ends of the collar. Such structure however does not accomplish the results that my collar accomplishes in that it has no transverse unreinforced areas corresponding to the gaps 8 or has no reinforcing means for the front portions of the collar when the collar is buttoned up, hence when the tie is drawn close the front part of the collar will tend to wrinkle and present an unsightly appearance. Furthermore, such collar when laundered will have a well defined crease at about the positions where the gaps 8 occur in my collar. It will, therefore, be seen that my collar possesses marked advantages over such prior art collars, including the elimination of tabs on the collar.

From the foregoing description taken in connection with the accompanying drawing the construction, uses and advantages of my invention will be clear to those skilled in the art.

40 What I claim is:

1. In a shirt which includes a body and a collar capable of two positions, the improvement which includes: a turn-down collar having an inner edge secured to the shirt body, said collar including an exposed portion and a lining, said lining being substantially co-extensive with the said inner edge, a reinforcing means located in the neckband area of the collar and having its inner edge shaped to comprise a folding guide when the collar is to be used with a necktie, said reinforcing means being formed in three separated parts, the two end parts being separated from the middle part to form two upwardly converging folding portions at approximately the

shoulder line of the shirt to which the collar is attached, the two end parts of the reinforcing means extending along the end edges of the collar a distance approximately the width of the neck encircling part of a necktie, by virtue of all of which the collar when worn without a necktie will lie back smoothly as a sport collar and when worn with a necktie will have the necessary reinforcement to look neat in front like a dress collar.

2. In a shirt which includes a body and a collar capable of two positions, the improvement which comprises: a turn-down collar having an edge directly associated with the shirt body and including an exposed portion; a lining which is substantially co-extensive with the exposed portion of the collar; and a reinforcing means substantially co-extensive with said directly associated edge and located in the neck-band area and extending part way along the end edges of the collar, said reinforcing means having its edge that is remote from said directly associated edge shaped to constitute a folding guide when the collar is folded over and used with a necktie, said reinforcing means being formed in three parts with narrow transverse spaces between the parts, the adjacent edges of the three parts converging from said directly associated edge toward the edge of the reinforcing means that is remote from said directly associated edge, the central part of the reinforcing means being approximately twice

the length of an end part of the same, by virtue of all of which when the shirt is folded for shipment the collar will lie flat and when the collar is worn with a necktie the portions of the reinforcing means extending along the wings will hold up the fold of the collar without depending on the necktie to do the same.

3. In a shirt which includes a body and a collar capable of two positions, the improvement which 10 comprises a turn-down collar having an edge directly associated with the shirt body and including an exposed portion; a lining which is substantially co-extensive with the exposed portion of the collar; and a reinforcing means approximately coextensive with said directly associated edge and located in the neckband area of the collar, said reinforcing means having its edge that is remote from said directly associated edge shaped to constitute a folding guide when the collar is folded over for use with a necktie, said reinforcing means being formed in three parts with narrow transverse spaces between the parts, said transverse spaces being located at approximately the shoulder line of the shirt to which the 20 collar is attached, by virtue of all of which the collar when worn without a necktie will lie back smoothly as a sport collar and when worn with a necktie will have the necessary reinforcement to look neat in front like a dress collar.

ARTHUR POWELL.
